COMBINED KEYBOARD AND CABINET FOR PRINTING TELEGRAPH APPARATUS

Donald M. Genaro, Fort Lee, N.J., and Eugene K. Sokolowski, Chicago, and Walter J. Zenner, Des Plaines, Ill., assignors to Teletype Corporation, Skokie, Ill., a corporation of Delaware

Filed Dec. 6, 1961, Ser. No. 67,824

Term of patent 14 years

(Cl. D64—11)

FIG. 1

FIG. 2

FIG. 1 is a front perspective view of a combined keyboard and cabinet for printing telegraph apparatus showing our new design; and

FIG. 2 is a rear perspective view thereof.

We claim:

The ornamental design for a combined keyboard and cabinet for printing telegraph apparatus, substantially as shown.
